UNITED STATES PATENT OFFICE.

OTTO C. KINNEY, OF INDIANAPOLIS, INDIANA.

NOISELESS SWING-SUPPORT.

1,285,227.

Specification of Letters Patent. Patented Nov. 19, 1918.

Application filed November 11, 1916. Serial No. 130,898.

To all whom it may concern:

Be it known that I, OTTO C. KINNEY, a citizen of the United States, residing at Indianapolis, in the county of Marion and 5 State of Indiana, have invented a new and useful Noiseless Swing-Support, of which the following is a specification, reference being had to the accompanying drawings and to the letters and figures of reference 10 marked thereon.

This invention relates to appliances for supporting swings of various types, or hammocks, the invention having reference more particularly to supporters for the suspension 15 chains of porch swings.

An object of the invention is to provide improved means for supporting cables or chains in such manner as to permit them to swing nearly or quite noiselessly and without requiring frequent lubrication. Another 20 object is to provide improved means for supporting porch swings so that the suspension chains of the swing seat shall not cause the disagreeable noises common to the ordinary 25 porch swing because of lack of lubrication and rusting of the iron chains found to be the most desirable for the purpose designed.

With the above-mentioned and other objects in view the invention consists in an 30 improved hanger having an anti-friction bearing and constructed in a novel manner, the invention consisting also further in the parts and combinations and arrangements of parts as hereinafter particularly described and further defined in the accompanying 35 claim.

Referring to the drawings.—Figure 1 is a side elevation of the improved hanger represented as being attached to an over-head support and supporting a chain so that 40 the chain may swing pivotally under the over-head support; Fig. 2 is a section of the hanger on the line II—II on Fig. 1; Fig. 3 is a front plan of the stationary part of the improved hanger; Fig. 4 is a central section 45 of the complete hanger taken on a plane at right angles to the plane of the line II—II; Fig. 5 is a sectional plan of the movable part of the hanger inverted; and Fig. 6 is 50 a section of the stationary part of the hanger slightly modified.

Similar reference characters on the different figures of the drawings indicate like elements or features of construction herein 55 referred to.

On the drawings the numeral 1 indicates

a suitable over-head support, such as a ceiling timber of a porch or other structure.

The improved hanger or support includes a stationary part which comprises a base 60 portion 2 having holes 3 and 4 and preferably also other holes 5 and 6, to receive securing screws 7 and 8 whereby the base portion of the part is rigidly secured to the underside of the over-head support. The 65 base portion has two ears 9 and 10 thereon to which a suitable bearing member is secured. Preferably a bearing member 11 is rigidly secured between the ears by means of a rivet 12, and the normal upper portion 70 of the member which is between the ears is provided with a circumferentially extending track groove 13 in which a bearing ball 14 is supported. As shown the track groove extends continuously around 75 the bearing member, being thus cheaply and conveniently produced.

The movable part of the hanger comprises a main suspension portion 15 from which extends a supporting crook 16 that 80 is adapted to rest or to roll upon the bearing ball, a beak portion 17 extending from the portion 16 so as to be approximately parallel to the portion 15 and with the latter serving to guard against accidental dislodgment of the movable part from the bearing member. The portion 16 has a track groove 18 thereon to receive the uppermost portion of the bearing ball. The movable part of the hanger has a hook 90 formed as a crook 19 extending from the main portion 15 and a curved beak 20 extending from the crook 19, the hook being adapted to support a link 21 of a chain or other device whereby an article may be 95 swingingly supported.

In some cases a bearing member 22 is rigidly secured between the ears of the stationary part of the hanger, as by means of a rivet 23 that is square in cross section so 100 as to prevent the accidental rotation of the bearing member, and the normal upper portion which is between the ears has a relatively short guide groove 24 therein adapted to receive the bearing ball and permit the 105 ball to roll a sufficient distance as the movable part of the hanger swings.

In practical use the improved hanger or support may in some cases be used singly or may be used in pairs as required for a 110 porch swing of the popular type. The movable part of the hanger is supported solely

by the bearing ball and normally is guided by the ball and the track grooves as the movable part swings relatively to the stationary part of the hanger, so that no frictional contact of the parts occurs and therefore rubbing contact that tends to produce disagreeable noises is obviated and the necessity for lubrication avoided.

Having thus described the invention, what is claimed as new is—

A hanger appliance comprising a stationary part having two depending ears, a bearing member secured between the ears, a

movable part comprising a carrying hook having a supporting crook adapted to loosely embrace the bearing member, the inner side of the crook having a guide groove of limited length and a bearing ball arranged in the guide groove to roll on the bearing member.

In testimony whereof I affix my signature in presence of two witnesses.

OTTO C. KINNEY.
